H. R. EVANS.
SOAP DISPENSING MACHINE.
APPLICATION FILED DEC. 10, 1910.

1,108,982.

Patented Sept. 1, 1914.

UNITED STATES PATENT OFFICE.

HENRY R. EVANS, OF NEW YORK, N. Y., ASSIGNOR TO GRANULATOR SOAP COMPANY,
A CORPORATION OF NEW YORK.

SOAP-DISPENSING MACHINE.

1,108,982.

Specification of Letters Patent.

Patented Sept. 1, 1914.

Application filed December 10, 1910. Serial No. 596,578.

To all whom it may concern:

Be it known that I, HENRY R. EVANS, a citizen of the United States, and a resident of New York city, county and State of New York, have invented certain new and useful Improvements in Soap-Dispensing Machines, of which the following is a specification.

My invention relates to soap dispensing machines, and more particularly to machines for dispensing solid soap.

One of the objects of my invention is to provide an efficient and durable soap dispensing machine by means of which the interlocks on the cakes of soap which hold them from relative rotation may be done away with.

More specifically, the object of my invention is to provide a machine of this type in which the cakes of soap are held together and into engagement with the cutter, in such manner as to obtain a proper dispensing of the soap, and the entire consumption of the successive cakes without waste due to the breaking and crumbling of the cakes when they become greatly reduced in thickness. In the preferred form of my invention, I accomplish this by providing a dished cutter with a coaxial soap-locking device held in close proximity thereto, and of such shape and construction as to insure the entire consumption of the reduced cakes of soap.

Another object of my invention is to produce relative motion between the locking device and cutter by means of a spindle passing centrally through the cakes of soap.

Other objects of my invention, such as the manner of supporting and arranging the coöoperating parts of my machine, will more fully hereinafter appear.

The present embodiment of my invention is illustrated in a machine which is of the same general construction and appearance as that disclosed in an application to Otis H. Kean and myself Serial No. 572,318, filed July 16, 1910; but I do not wish to be understood as limiting the different features of my invention to this or any other type or form of machine other than as specifically pointed out in the appended claims, since different features of my invention may be used in various combinations in different types of machines.

My invention will best be understood from

the following description taken in connection with the accompanying drawings in which—

Figure 1 is an elevation, partly in section, of a machine illustrating the present embodiment of my invention; Fig. 2 is a perspective view of a part of the same, showing the preferred form of cutter and soap-engaging and locking means; Fig. 3 is an elevation of the form of cutter used in the present embodiment of my invention; and Fig. 4 is a view looking down upon the inside of the soap follower which, in the present form of my invention, is the upper member of the receptacle, and showing cavities or depressions therein which register with the upper end of the soap-locking device.

Referring to the drawings, Fig. 1: 1 is an inclined supporting shank having an enlarged head 2 which may be in the form of a collar or projection secured to the top of the shank, or it may form an integral part of the shank as shown in the illustration.

In the present embodiment of my invention, a cylindrical member 3 forming one of the receptacle members for the soap, is secured to the head 2 in any desired manner, and as illustrated in the drawing, it may consist of a section of brass tubing suitably secured to the head 2 by pins or otherwise. The shank 1 is provided with a socket or passageway 4 formed therein, for receiving and concealing a spindle 5 hereinafter referred to. The lower part of this socket or passageway is preferably formed with a tapering portion 6, and a tube 7 is inserted in the socket or passageway, and is centered therein upon the curved portion 6. The tube 7 is secured within the socket in any desired manner, and the shank head 2 may be turned down in any suitable manner to fit the cylindrical member 3.

In the present embodiment of my invention, I provide a lock case 8 mounted on top of the floor member or enlarged shank head 2 and fastened thereto by any suitable means and having a part 9 fitting concentrically over the tube 7 to properly adjust and hold it from lateral movement with respect to the tube, and to form a level seat for the cutter. The lock casing, in this instance, constitutes a part of the bottom or end member of the receptacle. Within this case is mounted a spring-pressed locking finger or plunger 10, the head of which projects

through a suitable opening 11 in the wall of the tube, and into engagement with the spindle 5. The particular construction and arrangement of this lock casing and the locking plunger 10, as well as the construction and arrangement of the hollow shank and enlarged head 2, form no part of my present invention, the same being fully described and claimed in the above mentioned 10 application Serial No. 572,318.

The lock case 8 and the shank head 2 upon which the case is mounted, are of such shape and size as to leave a suitable opening 12 at one end of the receptacle through which 15 the soap is dispensed.

Within the receptacle a suitable cutter is provided for dispensing the soap, and in the present embodiment of my invention a dished cutter 13 is utilized, which is mounted at the delivery end of the receptacle, fitting loosely and concentrically over the tube 7. The cutter has a slight clearance with respect to the cylindrical member 3, and is provided with a projection 14 extending 20 loosely between the tube and the lock casing, and loosely engaging the locking finger, thus permitting a certain amount of movement of the cutter, but preventing its withdrawal. On account of this loose fit of the cutter 25 within the receptacle and its loose engagement with the finger and the adjacent parts, the cutter may center itself with respect to the soap, thus maintaining an automatic balance of external forces on the soap and 30 reducing any tendency of the soap to bind around the central shaft, thus diminishing the consequent liability of splitting the soap.

In order to dispense with the interlocks between adjacent cakes of soap, which have 40 been heretofore used for transmitting motion from one cake to the other, it has been proposed to use fins or webs engaging in grooves in the cakes of soap to lock them together during the dispensing process; but 45 in all of the arrangements heretofore used, the construction and arrangement of the soap-locking device and the cutter have been such that after the cake of soap adjacent the cutter has been consumed so as to leave a 50 thin section of soap, the stresses and strains produced in the soap by means of the relative rotation of the locking device and cutter, have caused the reduced cake of soap to crack and crumble into fragments which 55 were allowed to fall through the delivery end of the receptacle, resulting in the waste of this portion of the cake, thus rendering such devices unfit for practical commercial use. In order to overcome these difficulties, 60 I propose to provide a soap-engaging and locking device which engages the cakes of soap centrally, and which is positioned in extremely close proximity to the cutter; and in the best embodiment of my invention, I 65 utilize dished cutters which may be conical

or bowl shaped, and I mount the soap-locking device in close proximity to the smooth inner surface thereof with the extremity of the soap-locking part adjacent the cutter formed substantially parallel to the adjacent 70 face of the cutter. Such a construction is shown in the present embodiment of my invention in which the soap-locking device 75 consists of a sleeve 16 having one or more, and preferably at least three, radial projecting fins 17 the extremities 18 of which adjacent the cutter are made inclined so as to be parallel with the adjacent wall of the cutter. In the present embodiment of my invention, this sleeve is held in position above the cutter by means of an inward radial projecting tip or lug 19, the lower end of which rests upon the top of the hollow sleeve 7. The soap-locking device extends a certain distance above the cylindrical casing 3, for reasons hereinafter mentioned. 80

The soap-locking device, in the present form of my invention, is arranged rotatively, and is driven by means of the spindle 5 extending from the head 20 of an upper receptacle member 21, and provided with a vertical groove 22 into which extends the inwardly projecting tip 19 of the sleeve 16. The spindle 5 is provided with a series of grooves 23 which may be ratchet shaped, and 90 into which the locking plunger 10 extends. By means of these grooves or steps cut in the spindle, which may be arranged at any desired distance apart, the locking finger engages above the shoulder of each groove as 95 the spindle is fed down into the sleeve 7, thus effectually preventing the upper receptacle member from being lifted from any position which it assumes during the dispensing process, and then slammed down 100 upon the soap, resulting in the breaking of the soap or displacement and disarrangement of the internal parts of the machine, but permitting the spindle to move down as 105 the soap is consumed. 110

In order that a fresh cake of soap may be placed in the machine before the upper receptacle member moves down to its lowest position, namely, with the inner surface of the head 20 in engagement with the upper rim of the receptacle 3, I arrange the soap-locking device to extend a certain distance above the upper rim of receptacle 3, and I then provide cavities, grooves or openings 24 in the soap follower member which, in the 115 present instance, is the head 20. After a certain amount of soap has been consumed, the upper end of the locking projections telescope in these cavities until a fresh cake 120 of soap is placed in the machine. 125

With the arrangement and particular construction of the embodiment of the invention shown, the machine can not be refilled until the upper receptacle member has moved down low enough for the upper edge 13

of the locking device to telescope with the 5 cavities 22 in the head, since there will be no projecting portion of the soap-locking device above the soap to engage the new cake until the upper end of the soap has been fed down below the projection of the locking device. By the use of a dished cutter, and more especially a conical cutter, the breaking and crumbling of the reduced 10 cakes of soap is greatly lessened, if not entirely overcome. This is due to the fact that the smooth surface of the cutter supports the soap on all sides, and the central portion of the reduced cake of soap, where 15 it is engaged by the locking device, is relatively thick in cross section, and also the leverage of the cutter on the soap is relatively small.

In the present embodiment of my invention, the conical cutter and the soap-engaging device with its plurality of radial projections tapered in the manner shown, form together a plurality of conical compartments which, even if the reduced cake of 25 soap adjacent the cutter should crumble after being practically used up, the fragmentary parts of the cake would be firmly confined in these conical compartments, and, being pressed down upon the cutter by the 30 pressure of the adjacent upper cake of soap, will be held compactly and forced into engagement with the cutter so as to be dispensed in fine granules or shavings until completely consumed.

35 While I have described with particularity the present embodiment of my invention, namely, in connection with a machine having a stationary cutter arranged concentric with a revolving soap-locking device, and 40 with the receptacle members telescoping during the dispensing operation, it is obvious that certain broad features of my invention are not limited to any particular form or type of machine.

45 Numerous combinations of certain features of my invention will readily suggest themselves to those skilled in the art, which combinations may be utilized with various forms and types of machines now 50 known; and as far as relates to certain broad features of my invention, I do not wish to be understood as limiting myself to a machine having telescoping receptacle members, or to the use of stationary cutters, 55 or cutters of any particular form or construction, or to a concentric arrangement of the cutter and soap-locking device, or to the particular construction of the soap-locking device or any other feature; other than as 60 particularly pointed out in the appended claims.

Having thus described my invention, what I claim as new and desire to secure by Letters Patent, is:

65 1. In a soap dispensing machine, the com-

bination of a soap receptacle, a dished cutter in engagement with and surrounding one extremity of the soap to be dispensed, a device engaging and locking together the adjacent cakes of soap, said device being positioned adjacent the cutter substantially concentric therewith and extending toward the cutter beyond the upper edge thereof, a spindle extending above and below said device and journaled at its end adjacent the cutter, and means for producing relative movement between said device and cutter. 70

2. In a soap dispensing machine, the combination of a soap receptacle, a dished cutter in engagement with and surrounding one extremity of the soap to be dispensed, a device engaging and locking together the adjacent cakes of soap, said device being positioned adjacent the cutter substantially concentric therewith and a spindle passing through said device and connected to rotate therewith, and means for rotating said spindle and device. 80

3. In a soap dispensing machine, the combination of a soap receptacle, a dished cutter in engagement with and surrounding one extremity of the soap to be dispensed, a device engaging and locking together the adjacent cakes of soap, said device being positioned adjacent the cutter substantially concentric therewith and extending into close proximity to the apex of the cutter, a rotating spindle passing through said device, and means rotating the spindle and causing relative movement between said cutter and device. 90

4. In a soap dispensing machine, the combination of a soap receptacle, a dished soap cutter mounted at the delivery end of said receptacle, and means engaging the cakes of soap to lock them together, said locking means also mounted at the delivery end of said receptacle coaxial with said cutter and extending toward the cutter beyond the outer end thereof and relatively movable rotatively with respect thereto. 105

5. In a soap dispensing machine, the combination of a soap receptacle, a stationary dished soap cutter mounted at the delivery end of said receptacle, and means engaging the cakes of soap to lock them together, said locking means also mounted at the delivery end of said receptacle coaxial with said cutter, and a spindle extending on each side of said locking means and journaled at the end thereof adjacent the cutter, and means for rotating the spindle and locking means. 115

6. In a soap dispensing machine, the combination of a soap receptacle, a projection from the delivery end thereof, a soap cutter supported from said end substantially coaxial with said projection, and means engaging the cakes of soap to lock them together, said means also supported from the delivery end substantially concentric with the projec- 125

tion and relatively movable rotatively with respect to said projection.

7. In a soap dispensing machine, the combination of a soap receptacle having a bottom from which it is supported, a projection from said bottom, a soap cutter supported by said bottom substantially coaxial with said projection, and means engaging the cakes of soap to lock them together, said means also supported by the bottom substantially concentric with the projection and relatively movable rotatively with respect to said projection.

8. In a soap dispensing machine, the combination of a soap receptacle, a projection from the delivery end thereof, a soap cutter also supported from the delivery end and through which said projection passes, and a device engaging and locking the cakes of soap together, mounted on said projection and rotatively movable with respect to the cutter.

9. In a soap dispensing machine, the combination of a soap receptacle having a bottom from which it is supported, a projection from said bottom substantially coaxial with the receptacle, a soap cutter supported by said bottom and through which said projection passes, and a device engaging and locking the cakes of soap together, mounted on said projection and rotatively movable with respect to the cutter.

10. In a soap dispensing machine, the combination of a soap receptacle, a projection from the delivery end thereof, a stationary soap cutter supported at the delivery end and through which said projection passes, and a device engaging and locking the cakes of soap together, mounted rotatively on said projection and supported thereon in close proximity to but out of contact with the cutter, and means for rotating said device.

11. In a soap dispensing machine, the combination of a soap receptacle having a bottom from which it is supported, a projection from said bottom substantially coaxial with the receptacle, a stationary dished soap cutter supported by said bottom and through which said projection passes, and a device engaging and locking the cakes of soap together, mounted rotatively on said projection and supported thereon in close proximity to, but out of contact with the cutter, and means for rotating said device.

12. In a soap dispensing machine, the combination of a soap receptacle, a soap cutter mounted at the delivery end of the receptacle, a hollow projection extending from said end, a device engaging and locking the cakes of soap together, mounted rotatively on said hollow projection, and a spindle fitting within said hollow projection and engaging said device to rotate the cakes of soap relative to the cutter.

13. In a soap dispensing machine, the com-

bination of a soap receptacle, a dished soap cutter mounted in the lower part of the receptacle, a hollow projection extending from the lower part of the receptacle, a device engaging and locking the cakes of soap together, mounted rotatively on said hollow projection, and a spindle fitting within said hollow projection and engaging said device to rotate the cakes of soap relative to the cutter.

14. In a soap dispensing machine, the combination of a soap receptacle having an end member, a tubular projection extending from the end member, a stationary soap cutter fitting over said projection, a device engaging and locking the cakes of soap together and mounted rotatively on said tubular projection, and a spindle fitting within said tubular projection and engaging said device to rotate the cakes of soap.

15. In a soap dispensing machine, the combination of a soap receptacle having an end member, a stationary soap cutter mounted on said end member, a tubular projection extending centrally from said member through the cutter, a sleeve mounted on the tubular projection and provided with one or more radial fins engaging and locking the cakes of soap together, and a spindle fitting within the tubular projection and engaging the sleeve to rotate the cakes of soap with respect to the cutter.

16. In a soap dispensing machine, the combination of a soap receptacle, a hollow projection from one end of said receptacle, a soap cutter supported at said end of the receptacle, a device engaging and locking the cakes of soap together, mounted rotatively on the hollow projection above the cutter, and a rotatable spindle extending through the receptacle into the hollow projection and having a sliding connection with said soap-engaging device for rotating the soap relative to the cutter.

17. In a soap dispensing machine, the combination of a soap receptacle having an end member, a tubular projection extending from said end member, a stationary soap cutter fitting over said projection, a device engaging and locking the cakes of soap together and mounted rotatively on said tubular projection, a spindle fitting within the tubular projection and movable longitudinally therein during the dispensing process, and a sliding connection between the soap-engaging device and said spindle for rotating the cakes of soap with respect to the cutter.

18. In a soap dispensing machine, the combination of a receptacle having an end member, a tubular projection from said member, a dished soap cutter supported on said member, a sleeve rotatively mounted on said projection above the cutter and provided with three or more fins engaging and

locking the cakes of soap together, a rotatable spindle extending through the receptacle and into said tubular projection and movable longitudinally therein during the dispensing process, and a sliding connection between said spindle and sleeve whereby the cakes of soap are rotated relative to the cutter.

19. In a soap dispensing machine, the combination of a receptacle member, a soap cutter supported on said member, a tubular projection extending within the receptacle from said member, a device rotatively mounted on said tubular projection and above the cutter for engaging and locking the cakes of soap together, a second receptacle member rotatable with respect to the first member, and a central projection from said second receptacle member extending within the tubular projection from the first member and engaging said soap-locking device, whereby the cakes of soap are rotated relative to the cutter.

20. In a soap dispensing machine, the combination of a receptacle member, a stationary dished soap cutter supported on said member, a tubular projection extending within the receptacle from said member and through the cutter, a device rotatively mounted on said tubular projection and above the cutter for engaging and locking the cakes of soap together, a second receptacle member rotatable with respect to the first member, and a central projection from said second receptacle member extending within the tubular projection and engaging said soap-locking device, whereby the cakes of soap are rotated relative to the cutter.

21. In a soap dispensing machine, the combination of a dished cutter, a device locking the cakes of soap together and arranged substantially concentric with the dished cutter, the extremity of the soap-engaging and locking portion of said device adjacent the cutter being formed substantially parallel with and arranged in close proximity to the adjacent surface of said cutter, and means for producing relative motion between said cutter and said soap-engaging and locking device.

22. In a soap dispensing machine, the combination of a dished soap cutter, a device engaging and locking together the cakes of soap to be dispensed, said device consisting of a sleeve having a plurality of radial fins the extremities of which adjacent the cutter are formed parallel with and arranged in close proximity to the adjacent surface of said cutter, means for supporting said device in close proximity to the cutter, and means for causing relative movement between said device and said cutter.

23. In a soap dispensing machine, the combination of a soap receptacle member, a stationary dished soap cutter mounted at one

end thereof, a device mounted concentric with the cutter and engaging and locking the cakes of soap together, consisting of a sleeve having three or more radial fins the ends of which adjacent the cutter are formed parallel with the adjacent surface of the cutter, means for supporting said device substantially adjacent and in close proximity to the cutter, and means for producing relative rotative movement between said soap-engaging and locking device and said cutter.

24. In a soap dispensing machine, the combination of a receptacle having an end member, a tubular projection from said member, a dished soap cutter supported on said member, a sleeve mounted on said projection adjacent the cutter and provided with one or more fins engaging and locking the cakes of soap together, the ends of the fins adjacent the cutter being substantially parallel with the adjacent surface of said cutter, a rotatable spindle extending through the receptacle and into said tubular projection, and means rotating said spindle and device.

25. In a soap dispensing machine, the combination of a receptacle member, a dished soap cutter supported on said member and in turn supporting the cakes of soap, a tubular projection extending within the receptacle from said member, a device rotatively mounted on said projection and above the cutter for engaging and locking the cakes of soap together, said device having a plurality of radial fins the lower extremities of which are substantially parallel with and in close proximity to the adjacent surface of the cutter, a second receptacle member rotatable with respect to the first member, and a central projection from said second member extending within the tubular projection from the first receptacle member and engaging said soap-locking device, whereby the cakes of soap are rotated relative to the cutter.

26. In a soap dispensing machine, the combination of a receptacle member, a stationary dished soap cutter supported on said member and in turn supporting the cakes of soap to be dispensed, a tubular projection extending from said member within the receptacle and through the cutter, a soap-locking device consisting of a sleeve rotatably mounted on said tubular projection above the cutter and provided with a plurality of radial fins engaging and locking the cakes of soap together, the lower ends of said fins being substantially parallel with and in close proximity to the adjacent surface of said cutter, a projection extending inwardly from said sleeve to support the same on the tubular projection, a second receptacle member rotatable with respect to the first member, and a central projection from said second receptacle member extending within the tubular projection and pro-

vided with a longitudinal groove into which the projection from said sleeve extends, whereby the cakes of soap may be rotated relative to the cutter.

5 27. In a soap dispensing machine, the combination of a soap receptacle, a soap cutter mounted at one end thereof, means engaging the cakes of soap and locking them together, said locking means being supported coaxial with said cutter and adjacent thereto, a follower for the cakes of soap having cavities or openings therein corresponding to the cross section of said soap-locking

and engaging device, whereby the follower may telescope with said device during the dispensing process, and means for producing relative motion between the cakes of soap and said cutter including a handle rigid with the follower.

15 In testimony whereof, I have signed my name to this specification, in the presence of two subscribing witnesses.
